(57) **CLAIM**

The ornamental design for a communication circuit housing, as shown and described.

DESCRIPTION

FIG. 1 is a top perspective view of a communication circuit housing showing our design;

FIG. 2 is a bottom perspective view thereof;

FIG. 3 is an exploded top perspective view of the communication circuit housing;

FIG. 4 is an exploded bottom perspective view of the communication circuit housing;

FIG. 5 is a first side view of the communication circuit housing;

FIG. 6 is second side view thereof, opposite that shown in FIG. 5;

FIG. 7 is another side view thereof, 90 degrees offset from that shown in FIG. 5;

FIG. 8 is another side view thereof, opposite that shown in FIG. 7;

FIG. 9 is a top view of the communication circuit housing; and,

FIG. 10 is a bottom view thereof.

The broken lines shown herein are for illustrative purposes only and form no part of the claimed design.

1 Claim, 5 Drawing Sheets
